CLAIM

The ornamental design for a reusable soap package, as shown and described.

DESCRIPTION

FIG. 1 is a closed perspective view of a reusable soap package.

FIG. 2 is a closed side view.

FIG. 3 is a closed top view.

FIG. 4 is a closed bottom view.

FIG. 5 is an open perspective view.

FIG. 6 is an open side view.

FIG. 7 is an open top view.

FIG. 8 is an open bottom view.

FIG. 9 is a separated perspective view.

FIG. 10 is a separated side view.

FIG. 11 is a separated top view; and,

FIG. 12 is a separated bottom view.

The broken line showing in the figures is included for the purpose of illustrating portions of the reusable soap package and form no part of the claimed design.
